UNITED STATES PATENT OFFICE.

WILLIAM ACKERMAN, OF NEW YORK, N. Y., ASSIGNOR TO THE UNITED STATES GRAPHOTYPE COMPANY, OF NEW YORK, N. Y., A CORPORATION OF NEW YORK.

SLACK-PROVIDER FOR PERFORATING-MACHINES.

SPECIFICATION forming part of Letters Patent No. 734,651, dated July 28, 1903.

Application filed December 5, 1902. Serial No. 133,973. (No model.)

To all whom it may concern:

Be it known that I, WILLIAM ACKERMAN, a citizen of the United States, residing at New York, in the county of New York and State of New York, have invented certain new and useful Improvements in Slack-Providers for Perforating-Machines, of which the following is a specification.

This invention relates to a mechanism which is designed for feeding a continuous strip of paper from a roll to the feed mechanism of a machine for perforating the strip.

It is absolutely necessary for the accurate operation of the automatic machine which is to be actuated by the perforations in the strip that the perforations be made in the correct positions and in exact relation with each other. To accomplish this, the strip must be fed regularly and evenly to the punching mechanism of the perforating-machine. If the strip is fed too fast or if there is a drag and the paper is not fed fast enough to the perforating-machine, the spaces between the perforations will vary and be irregular, and when the strip is put into the automatic machine, whether it be for casting type or transmitting messages, the proper contact-pins will not close the circuits necessary to produce the correct characters. Rolls

of paper coming from the manufacturer are sometimes rolled more tightly than they are at other times. When they are rolled tightly, there is more of a strain upon the feed mechanism than when they are rolled loosely, and

when there is a strain upon the feed mechanism there is a liability that shorter lengths of the paper will be fed than when there is no strain upon the feed mechanism. There is also a different strain on the feed mechanism when the strip is being pulled from the periphery of a roll of large diameter than when the strip is being pulled from the periphery of the roll that has been reduced and is small in diameter. This affects the feed

of the paper to a perforating-machine and results in irregularly-punched perforations, and these cause the machine which is actuated by the perforations to operate inaccurately.

The object of this invention is to produce

a simple, easily-handled, and closely-adjustable slack-provider—that is, a mechanism which will act synchronously with and pass the strip of paper from the roll to the feed mechanism of the perforating-machine regularly and evenly, so that the tension will always be the same, and consequently the exact amount of paper will be fed at each interval to the punches and the perforations made in the proper positions and at the correct distances from each other to cause the accurate operation of the machine with which the perforated strip is to be used. This object is attained by providing a standard with a fork for supporting the roll of paper, with rolls for feeding the paper, a ratchet-and-pawl mechanism for intermittently rotating the feed-rolls, and a magnet for actuating the pawl, the magnet being adapted to be connected with the circuit which operates the feed mechanism of the perforating-machine. A friction device is attached to the fork to prevent the roll of paper from running ahead and unwinding too fast, and an adjustable tension device is provided for regulating the pressure of the feed-rolls upon the paper.

Figure 1 of the accompanying drawings is a side elevation of a slack-provider that embodies the invention. Fig. 2 is a rear elevation of the same, and Fig. 3 is a detail view showing the paper-roll friction device on larger scale.

The supporting-base 1, the standards 2, rising from the base, and the arms 3 of the fork projecting from the standard are preferably cast integral of iron. In the upper ends of the arms are slots 4 for receiving the ends of the spindle 5 of the bobbin 6, upon which the strip of paper is wound. On one side the bobbin has a flange 7 and on the other side has a finger 8. The roll of paper is held on the bobbin between the flange and the finger.

To prevent the roll from turning ahead and unwinding too rapidly when the strip of paper is pulled by the feed-rolls, a pin 9 is caused to impinge against the flange on the end of the bobbin by a spring 10 in the hub 11, that projects from the side of the upper end of one arm. The tension of this spring is adjusted by means of the screw-threaded sleeve 12, that

turns in the threaded end of the hub. A clamp-nut 13 is provided for holding the sleeve in position after it has been turned to obtain the desired tension for the spring.

5 The feed-rolls 14 and 15 are mounted on arbors that are held by the arms of the fork. The arbor 16 of the lower roll at one end has a gear 17, that meshes with a gear 18 on the arbor 19 of the upper roll. The ends of the 10 arbor 19 of the upper roll extend through slots in the arms of the fork and are engaged by yokes 20 on the ends of spindles 21, which are pressed down by springs 22, that thrust 15 between nuts 23 on the spindles and lugs 24, projecting from the arms of the fork. By turning the nuts the tension of the springs may be adjusted, so that the pressure of the upper roll against the lower roll may be closely regulated. On the upper end of each 20 of these spindles is a head 25, and pivoted to the end of each lug and adapted to engage the head of a spindle is a lever 26. When these levers are turned down, the spindles are raised, so as to relieve the pressure of the upper roll against the lower roll. When the levers are thrown up, the spindles are forced 25 down by the springs, so that the upper roll bears against the lower roll with the desired yielding pressure.

30 On one end of the arbor 16 of the lower roll is a ratchet 27. Engaging with the teeth of this ratchet is a pawl 28, that is pivoted to the side of one of the arms of the fork. Engaging with the teeth of this ratchet there is also 35 a pawl 29, that is mounted on a lever 30, which is free to oscillate on the arbor 16 of the lower roll. The end of this lever opposite the pawl is connected by a link 31 with the end of an armature-lever 32, that is pivoted to an arm 40 33, which projects forwardly from the upper end of the standard. The armature-lever carries the armature 34 of the two magnets 35, the coils of which are adapted to be connected, preferably in parallel, with the wires of the 45 circuit which operates the feed of the perforating-machine with which this slack-provider is to be used. A spring 36 normally lifts the armature-lever and holds the armature away from the magnet-cores. A screw 37, held by 50 the arm 33, is arranged to engage the top of the armature and limit the upward movement of the armature-lever, and a screw 38 is arranged to engage the bottom of the armature and limit the downward movement of the lever. By these means the feeding movement 55 of this lever can be adjusted to a nicety.

An insulating-block 39 is secured to the standard for supporting the binding-posts 40, to which the circuit-wires are connected. 60 The binding-posts are connected with resistance-coils 41, which are connected with the coils of the feed-magnets.

With this slack-provider a strip of paper may be fed from a large or small roll wound 65 tightly or loosely, so that there will be no tension on the paper when it passes into the feed of the perforating-machine with which

this slack-provider is designed to be used. All of the parts are adjustable, so that the feed of the paper by this slack-provider may 70 exactly equal the feed of the perforating-machine.

I claim as my invention—

1. A slack - provider having a standard adapted to support a roll of paper, feed-rolls 75 supported by the standard and geared together, a ratchet-and-pawl mechanism adapted to intermittently rotate one of the feed-rolls, and a magnet arranged to actuate the pawl and adapted to be connected with the feed-circuit of a perforating-machine, substantially as specified.

2. A slack - provider having a standard adapted to support a roll of paper, a friction device adapted to retard the rotation of the 85 roll of paper, feed-rolls supported by the standard and geared together, a ratchet-and-pawl mechanism adapted to intermittently rotate one of the feed-rolls, and a magnet arranged to actuate the pawl and adapted to 90 be connected with the feed-circuit of a perforating-machine, substantially as specified.

3. A slack - provider having a standard adapted to support a roll of paper, feed-rolls supported by the standard and geared together, a tension device for regulating the pressure of one feed-roll against the other, a ratchet-and-pawl mechanism adapted to intermittently rotate one of the feed-rolls, and a magnet arranged to actuate the pawl and 95 adapted to be connected with the feed-circuit of a perforating-machine, substantially as specified.

4. A slack - provider having a standard adapted to support a roll of paper, feed-rolls 105 supported by the standard and geared together, an adjustable tension device adapted to regulate the pressure of one feed - roll against the other, a relief device for relieving the pressure of one roll from the other, a ratchet-and-pawl mechanism adapted to intermittently rotate one of the rolls, and a magnet arranged to actuate the pawl and adapted to be connected with the feed-circuit of a perforating-machine, substantially 110 as specified.

5. A slack - provider having a standard with a fork adapted to removably support a bobbin, an adjustable friction device adapted to control the movement of the bobbin, 120 feed-rolls supported in the fork and geared together, an adjustable tension device for regulating the pressure of one feed - roll against the other, a ratchet connected with an arbor of one feed-roll, a pawl engaging 125 the ratchet, and a magnet arranged to actuate the pawl and adapted to be connected with the feed - circuit of a perforating - machine, substantially as specified.

6. A slack-provider having a standard, a 130 fork projecting upwardly from the standard, openings in the upper ends of the fork adapted to receive the arbor of a paper-bobbin, an adjustable friction device held by 135

the standard and adapted to engage the bobbin for controlling its movement, feed-rolls geared together and held in the fork, an adjustable tension device adapted to regulate the pressure of one roll against the other, a device for lifting one roll from the other, a ratchet secured to the arbor of one roll, a pawl engaging the ratchet, a magnet adapted to intermittently actuate the pawl, adjust-

able means for determining the movement of the magnet-armature, binding-posts secured to the standard and resistance-coils fastened to the standard, substantially as specified.

WILLIAM ACKERMAN.
